STRAW SCATTERING ATTACHMENT

George H. Sheard, Athena, Oreg.

Application March 30, 1936, Serial No. 71,775

2 Claims. (Cl. 275—8)

This invention relates to straw scattering attachments for thrashers of the "combine" type, and the purpose of the invention is to scatter straw issuing from the thrashing machine as it is moving in the field where grain is being harvested.

It is an object of this invention to provide novel means for broadcasting or scattering straw delivered to the scattering instrumentalities from the thrashing machine so that the said straw may be distributed over a relatively wide area in a comparatively thin deposit, a condition which will facilitate the operation of plowing and the underturning of the straw.

15 It is a further object of this invention to provide novel means driven by power derived from the thrashing machine and moving with the thrashing machine for accomplishing the foregoing results.

20 It is a still further object of this invention to provide novel means for directing straw to the scattering instrumentalities and to provide scattering arms with blades at their ends, which blades are curved in the direction of rotation of the arms for the purpose of increasing the efficiency of the attachment.

25 With the foregoing and other objects in view, the invention consists in the details of construction, and in the arrangement and combination of parts to be hereinafter more fully set forth and 30 claimed.

35 In describing the invention in detail, reference will be had to the accompanying drawing forming part of this application, wherein like characters denote corresponding parts in the several views, and in which—

Figure 1 illustrates a view in elevation of a fragment of a thrashing machine with a device embodying the invention applied thereto;

40 Figure 2 illustrates a plan view thereof;

Figure 3 illustrates a rear elevation of an attachment in which one set of arms for each shaft is provided;

45 Figure 4 illustrates a plan view thereof; and Figure 5 illustrates a sectional view on the line 5—5 of Fig. 1.

In the drawing 5 denotes a conventional type of thrashing machine having the usual straw exit or open end 5^a and a rear extension 6 on which the scattering instrumentalities are mounted. Suitable driving gear may be provided, but the inventor does not wish to be limited with respect to this feature. However, a driven shaft 7 may be mounted on the thrashing machine and power thereof transmitted to the shaft

8 by which the scattering blades are driven, as will presently appear. It is shown that the shaft 8 is connected by suitable gearing to the shaft 7 in Fig. 1, which gearing in turn operates a part of the thrashing machine. In so far as it is the purpose of the inventor to have the scattering attachment operate at the time the thrashing machine is operating, any other suitable means may be provided for driving this scattering attachment.

5 The shaft 8 is rotatably mounted on the extension and it is provided with beveled gear wheels such as 9 and 10 which mesh with gear wheels 11 and 12, respectively. The gear wheels 11 and 12 are secured on vertically rotatably mounted shafts 13 and 14, respectively, and each shaft has a head 15 which may be in the nature of a collar or sleeve secured on it. In the arrangement shown, the shafts are rotated in opposite directions as indicated by the arrows. Each 20 head has a plurality of arms 16 extending outwardly and upwardly and the said arms are preferably channeled to form seats for the scattering blades or arms 17 secured thereto by appropriate fastenings 18 such as bolts or the like. 25 At the outer end of each arm, a blade or fin-like plate 19 is secured and the plate has its upper edge located above the surface of the arm and its end projecting beyond the arm. The extending end of the plate is curved as shown at 20 and 30 the bend in the direction of rotation of the arms, as indicated by arrows in the drawing. The preferable arrangement of the scattering instrumentalities is that they will operate to throw the straw laterally and rearwardly of the direction 35 of movement of the thrashing machine.

In order to more effectively direct the chaff or straw to the scattering instrumentalities, the rear end of the thrashing machine is provided with an inclined plate 21 shown in Figs. 1 and 2, the 40 said plate being omitted in Figs. 3 and 4 so that the structural features of the rearwardly extending portion of the thrashing machine may be seen. The plate is secured to the extension in any appropriate manner, as by fastenings 22 anchored 45 to the rearwardly projecting sills or members 23 of the aforesaid extension.

In Figs. 1 and 2, two sets of scattering instrumentalities are attached to each vertically disposed shaft, these being generally identified by 50 the reference letters A and B. When the two sets are employed the scattering arms of the upper set are located so that in plan they appear between the scattering arms of the lower set identified by the letter A. By reason of the elevated 55

position of the upper scattering arms, it will serve to propel the straw a somewhat greater distance before the straw reaches the ground and the use of the double set of scattering arms results in a 5 more uniform distribution of the straw.

As the functions of the elements and their operation have been given in connection with a description of the said elements, it is believed that the invention will be understood by those skilled 10 in the art.

I claim:

1. In a straw scattering attachment for thrashing machines operative while traveling, a supporting structure rearwardly of and below the straw discharging end of the thrashing machine, straw scattering means including vertically disposed shafts journaled in the said supporting structure, sets of arms, one set above the other, secured to the vertically disposed shafts extending 15 outwardly and upwardly therefrom in the path of movement of straw discharging from the thrashing machine, the arms of the lower set terminating above the plane on which the upper set of arms is connected to said shaft, means for rotating the shafts in opposite directions, a supporting plate extending from the open end of a 20 25

thrashing machine toward said shafts for directing straw to the scattering means, and blades on the outer end of each arm having their edges projecting beyond the edges of the arms and their ends projecting beyond the ends of the said arms, the said projecting ends being curved in the direction of rotation of the arms. 5

2. In a straw scattering attachment for thrashing machines operative while traveling, a supporting structure rearwardly of and below the straw discharging end of the thrashing machine, straw scattering means including vertically disposed shafts journaled in the said supporting structure, sets of arms, one set above the other, secured to the vertically disposed shafts extending outwardly and upwardly therefrom in the path of movement of straw discharging from the thrashing machine, the arms of the lower set terminating above the plane on which the upper set of arms is connected to said shaft, means for rotating the shafts in opposite directions, a supporting plate extending from the open end of a 10 15 20 25

GEORGE H. SHEARD.
